UNITED STATES PATENT OFFICE.

MAX LIVINGSTON, OF PHILADELPHIA, PENNSYLVANIA, ASSIGNOR TO ATLANTIC REFINING COMPANY, OF PHILADELPHIA, PENNSYLVANIA, A CORPORATION OF PENNSYLVANIA.

APPARATUS FOR CONTINUOUSLY DISTILLING PETROLEUM.

SPECIFICATION forming part of Letters Patent No. 728,257, dated May 19, 1903.

Application filed August 8, 1901. Serial No. 71,333. (No model.)

To all whom it may concern:

Be it known that I, MAX LIVINGSTON, a citizen of the United States, residing in the city of Philadelphia, in the county of Philadelphia and State of Pennsylvania, have invented 5 certain new and useful Improvements in Apparatus for Continuously Distilling Petroleum, of which the following is a specification.

10 My invention relates to distilling apparatus and its object is the provision of a simple, safe, economical, and efficient apparatus in which the distillation of crude petroleum may be carried on as a continuous operation.

15 In the accompanying drawings I show, and herein I describe, a good form of apparatus embodying my invention, the particular subject-matter claimed as novel being hereinafter definitely specified.

20 In the accompanying drawings,

Figure 1 is a view in top plan of a battery of stills arranged in accordance with a good form of my invention.

Figure 2 is a view in front elevation of the 25 stills shown in Figure 1.

Figure 3 is a view in elevation of a series of stills, the illustration being partly in section and on an enlarged scale as compared with Figures 1 and 2.

30 Figure 4 is a sectional elevation of the preparatory still 1, shown in Figure 3, section being on the line 4—4 of Figure 3.

Figure 5 is a sectional elevation of one of the vaporizing stills, for instance, that designated 2, section being supposed on the line 35 5—5 of Figure 3.

Figure 6 is a view of several stills illustrating a modified form of short connection.

Figure 7 is a detail of one of said short connections.

Similar letters of reference indicate corresponding parts.

In the initial distillation of the crude petroleum under the existing usual practice, the 45 operation is carried on until all the lighter oils have been vaporized, leaving the residuum to be subjected to subsequent independent operations.

My invention has especial, although not re-

strictive, relation to this initial distillation of 50 crude petroleum, and it is sought to enable said distillation to be carried on in as economical and efficient a manner as possible producing distillates of standard quality and grade, and at the same time preserving in the 55 residuum as large a proportion as possible of the elements useful in by products.

The vapors given off in this initial distillation are condensed and conducted to suitable receptacles, according to their character, for 60 further operations. The number of such receptacles and the sub-division or classification of the condensed vapors according to their grades or characteristics, may be extended as far as may be desired, and to such 65 end any required number, large or small, of stills and condensate receptacles may be employed.

In the drawings, 1, 2, 3, 4, 5, 6, 7, 8, 9, 10, and 11, are the stills of a series, shown as arranged side by side, on a foundation of masonry 36, which embodies a series of fire chambers 12, one situated beneath each still. Each still, with its fire chamber, is structurally independent of every other, except for 75 the connections hereinafter described. Each still is preferably formed as a cylindrical vessel of sheet iron, and placed upon its side across the top of its associated fire chamber.

At the back of the fire chambers of the first 80 two stills of the series after No. 1, are arranged up-takes 13, Fig. 5, discharging into a series of flues 14 which extend through the bodies of said stills Nos. 2 and 3, and discharge within the smoke boxes 15 each of 85 which is common to the group of flues of a single still, from which boxes lead suitable smoke stacks.

The remaining stills of the series may be provided at the backs of the fire chambers 90 with any suitable smoke stacks or other conveyers for the products of combustion, by which the latter are discharged at any suitable point or utilized in any desired manner,—the flues 14, as stated, not being ordinarily 95 used in such remaining stills of the series.

The passage of the smoke and products of combustion through the flues within the bod-

ies of the stills Nos. 2 and 3, of course, aids in elevating the temperature of the oil in said stills and thus economizes fuel.

16 are vapor pipes leading from the stills, 5 and through which the vapors or distillates are conducted to suitable condensers and collecting tanks, (not shown). Still number 1 which is what I term the preparatory still, is provided with an internal steam or other heating coil 17 (see Figure 4), the supply and discharge pipes 18 of which pass through the shell of the still, and through which coil is charged steam or hot fluid from any suitable source.

15 In practice I may supply said coil 17 with exhaust steam. Said coil 17 may, of course, be arranged in any desired manner. It is preferably arranged with its pipes separated from each other by suitable interspaces to allow the free precipitation of earthy matter contained in the oil, and may be supported by any suitable framework such as shown in Figure 3.

Referring now to the pipe connections, and 25 especially to the construction shown in Figures 1, 2, 3, 4, and 5, each pipe connection connective of two adjoining stills, and which connections are herein termed the short connections, is as to the portion of it which exists outside of the stills, of approximately U-shaped form, to constitute a suitable trap, such U-shaped portion being designated 19, and from the respective side members of such portion 19, branches lead to the interior of 30 the two stills connected, such branches, (especially the inlet or receiving branches, that is to say the branches into which the oil flows as it enters the short connections,) being provided within the respective stills with elbows 35 20 to which regulating sections, as I term them, 21, may be fitted and secured. As indicated in the several figures said regulating sections 21 are in screw threaded connection with the pipe elbows 20, from which they may 40 be unscrewed as desired.

45 The short connections, located at the rear of the stills, to wit, the ends thereof appearing in plan view at the upper edge of Figure 1 are preferably provided with cocks or valves, 50 by which the flow of oil through them may be shut off when desired. Those located at the front ends of the stills are preferably not so provided.

22, 23, and 24, are what I term long connections, arranged, in the embodiment illustrated, to connect respectively stills 7 and 10, 55 5 and 8, and 3 and 6. Except for being proportionately longer, the long connections are shown as of substantially the same construction as the short connections described.

26 is a pump connected by the pipe 25 with the last still of the series and adapted to pump residuum from said still.

27 is an oil supply pipe, connected with a 60 pump 28, by which the petroleum is charged to the preparatory still.

30 is a steam supply pipe having a branch

31 leading to the bottom of still No. 2, to assist in heating the oil in said still. If desired branches from said pipe 30 may lead to the 70 other stills of the series.

The operation of the apparatus will be readily understood.

The oil, as is well known, frequently contains more or less earthy matter, and a small 75 percentage of water, and I, therefore, equip the first or preparatory still with the heating coil, as described, to the end that the oil charged into said still may, as it passes about the pipes of the coil be acted upon throughout its body by the heat radiating therefrom, so that the water will be thoroughly separated from the oil and the earthy matter precipitated.

Any suitable cock controlled outlet 29 is 85 provided for drawing off the water and the precipitated earth from the bottom of the said preparatory still.

Incidental to the treatment of the oil in the first still vapor will be formed, which will, of course, pass off through the vapor pipe 16. The oil itself, freed from water and earthy matter, passes continuously from the preparatory still into still number 2, wherein it is heated and the lighter ingredients vaporized, 95 the vapor passing out through the vapor pipe 16 of said still No. 2. From still number 2 the oil continuously passes through the short connection to still number 3 wherein it is subjected to a suitable degree of heat and certain of its constituents vaporized, the portion not vaporized at the temperature maintained in said still number 3 passing through the short connection to still number 4, and so on.

The height of the receiving mouths or openings of the regulating pipes 21 of the connections 19 through which the oil from the individual stills passes into such connections and the succeeding stills, controls, of course, the liquid level in the several stills. Therefore, 100 by providing the elbows 20 at the receiving sides of the connections 19 with regulating sections 21 of suitable length, I may maintain the liquid level within the several stills at any desired graduated elevations. This 105 feature is of great importance.

By arranging said liquid receiving mouths of the several connections at successively lower levels in the series of stills the liquid will be caused to flow by gravity through the 110 series without requiring the aid of a pump or other artificial assistance.

The feature of preserving a graduated liquid level in the stills is, furthermore, of great importance with respect to those stills 115 which receive the heavier oils after the lighter oils have been vaporized. When, for example, the oil has passed through the first few stills of the series, and approximately fifty per cent. of its mass has been vaporized, the 120 oil remaining requires special operations to secure the best results.

It is desirable that the distillation shall be carried on in such manner as will occasion

the production of a satisfactory quality of distillates and at the same time avoid impairing the quality of the residuum.

Accordingly, when the oil has been reduced by the vaporization of approximately half its mass it is desirable in operating upon it in the remaining stills that the cubic space above the surface of the liquid in the stills should be very large and that the wall or walls of said still or stills should be remote from the direct action of the fire.

By reason of the high heat to which the oil is subjected, the vapors produced in a given still in the vicinity of the latter end of the series, may include not only the particular vapors which it is desired to produce by the vaporization of the oils in said still, but also a certain amount of the heavier products or constituents which it is desirable to have retained in the residuum, and said heavier products or constituents would, in the absence of special provision to the contrary, pass out through the vapor pipe from said still, with the result that the vapor so passing out would not be of required quality, and the mass of residuum which is received in and is pumped from the last still of the series for further operations in other apparatus,—would be deprived of valuable characteristics.

Accordingly, in operating upon such oil I prefer to maintain only such quantity of it in a still as will fill it about one third full, so that large vapor spaces above the liquid levels exist in the last stills of the series.

The vapors formed rise in such vapor spaces and circulate through them and about them and in contact with the upper walls of the stills, which are, as stated, out of contact with the fire, with the result that such of the heavier products naturally belonging in the residuum as are carried up into the vapor spaces referred to, will, in circulating about therein, becoming slightly cooler, fall back into the liquid and be transported to the next still and so on.

The operation of distilling is designed to be carried on in this apparatus until a heavy residuum remains, and this residuum is pumped from the last still or last several stills and conveyed away for special operations,—among which are included operations for separating it into sundry valuable products.

When, after continued use of the apparatus one or two of the stills have accumulated a deposit of coke, and it is desired to clean them, this may be done without interruption of the operation of the apparatus as a whole, as will be readily understood.

If, for example, it is desired to clean out stills numbers 6 and 7, the cocks in the two short connections 19, between stills 5 and 6 and 7 and 8 respectively are to be closed thereupon said stills 6 and 7 are, so to speak, cut out and isolated.

The cocks in the long connection 23 are opened. Thereupon in the operation of the

apparatus, the liquid from the still 5 instead of discharging through the connection 19 into still 6, discharges through said long connection 23 past stills 6 and 7, and into still 8, and from still 8 into still 9 and so on.

When the connection is established through the connection 23 as will be understood, the stills 6 and 7, are no longer included in the working series, and the oil from said stills may be run off, the fires extinguished, and any desired matter of cleaning or repair attended to.

After the two stills cut out of operation for cleaning or repair have been given whatever attention in such connection may be necessary, I supply them each with a body of oil at an ordinary temperature.

I then start up the fires beneath them, and the bodies of oil will, of course, be gradually increased in temperature, and the evaporation proceeded with.

When the oil in said stills has become heated to a high temperature and the liquid levels therein are approximately the levels at which the oil is ordinarily maintained in said stills I open the cocks in the two short connections by which said two stills are connected to the two adjoining stills and close the cocks in the long connection.

It will, of course, be understood that the oil is continuously supplied to the preparatory still, and that its flow through the successive stills is ordinarily continuous.

The vaporization contemporaneously proceeds in all the stills of the series as the oil flows through them, each still being maintained at that particular heat which experience has demonstrated to be best adapted for producing the particular distillate obtainable from its contents.

From the single battery of stills a constant flow of distillate is maintained through all the distillate pipes to the receptacles in which they terminate.

The cocks in the short connections are only used when it is desired to cut out of operation two of the stills as hereinbefore referred to, being then employed to cut off such two stills from communication with their neighbors.

The arrangement of the connections is such that those connections 19 which occur at the front of the apparatus are the connections which unite among others the individual members of the respective pairs of stills which are at times, as explained, by pairs cut out of operation.

As there is no necessity for cutting off connection between the two members of such a pair, the connections which unite the members of such respective pairs are not provided with cocks, and are placed at the front of the battery of stills.

The advantage of this arrangement is that all the cocks in the short connections are arranged at the rear of the stills where the heat is considerably less than at the front.

As hereinbefore explained, the heating mechanism or fire chamber of each still is controllable independently of, and is unaffected by, those of the other stills, and as a result of this arrangement, of course, the different stills may be maintained constantly each at its own temperature such as will insure the best results.

The arrangement of the fire chambers, regulating sections 21, and stills is such that the fire and products of combustion cannot come into contact with the walls of the stills above the level of the liquid therein. This is especially important where oil of the grade termed fifty per cent. oil and oils below such percentage are being operated upon, inasmuch as it enables the still walls above the liquid level to remain at a comparatively low temperature to occasion the cooling off of the vapor and to promote decomposition.

20 In the form of apparatus shown in Figure 6 I illustrate a modified arrangement of short connections. The short connections therein referred to are designated 32. Said short connections 32 correspond in general location and arrangement with the short connections 19 shown in plan view in Fig. 1, connecting successive pairs of the stills at alternately opposite ends thereof.

Each short connection 32 is at its respective extremities provided with branches which lead into the interiors of the respective stills connected.

35 The receiving branch of each such connection is at its inner end provided with a vertically arranged feeder pipe 33 the upper end of which extends to a point above the desired liquid level in the still in which it is situated and the other to a point in the vicinity of the bottom of said still.

40 Both ends of said feeder pipes 33 are open, and the bodies of said pipes are in direct communication with the interiors of the receiving branches of said short connections 32. In this construction the oil is taken from the bottoms of the several stills to supply the succeeding stills.

The preferred form of short connection, however, is that shown in connection with the two right hand stills of Figure 3, in which the 50 receiving regulator pipe 21 of each is equipped with a sleeve 35 encircling it and making a liquid tight connection with the receiving branch. The said sleeve, which acts as a feed controller, is open as to both ends, one end extending into the vapor space above the liquid level, and the other to a point near the bottom of the still.

55 In this arrangement while the liquid level inside the sleeve will be the same as that outside, all liquid within the sleeve will gain access thereto through its lower end, and all liquid drawn from the still through the pipe 21 will thus be taken from the bottom of said still.

65 The mouth of the pipe 21 constitutes the outlet from the still and controls the liquid level therein to the extent that the liquid is

not in the ordinary operation of the apparatus drawn down to a level below that of said mouth.

I do not claim herein or seek to cover the method of distilling petroleum herein outlined and which is adapted to be carried on in apparatus described, as such method forms the subject of an application for United States Letters Patent executed by me, and filed in the Patent Office contemporaneously herewith as serial number 71,334, dated August 8, 1901.

Having thus described my invention, I claim—

1. In an apparatus for continuously distilling petroleum, the combination with a series of distinct and independent stills; of a series of pipe connections which unite said stills in a continuous series; said connections each comprising an oil outlet from one still and an oil inlet to another still; said outlet having a regulating section arranged to adjustably determine the liquid level in the still associated therewith, substantially as set forth.

2. In an apparatus for continuously distilling petroleum, the combination with a series of distinct and independent stills; of a series of pipe connections which unite said stills in a continuous series; said connections each comprising an oil outlet from one still and an oil inlet to another still; said connections being exterior to the stills and having inlet and outlet branches opening upon the interiors of the respective stills connected thereby, and, the outlets being at different levels in the respective stills, substantially as set forth.

3. In an apparatus for continuously distilling petroleum, the combination with a series of distinct and independent stills; of pipe connections which unite said stills in adjoining pairs; said connections being exterior to the stills and having inlet and outlet branches opening upon the interiors of the respective stills connected thereby; and, the outlets occupying progressively lower levels in the successive stills, substantially as set forth.

4. In an apparatus for continuously distilling petroleum, the combination with a group of stills; of a series of pipe connections which unite said stills in a continuous series; said connections having inlet and outlet branches opening upon the interiors of the respective stills connected thereby; said outlet branches having vertical extensions within the respective stills, the mouths of which extensions are located at the points of the desired liquid levels therein; and, feed regulating sleeves respectively encircling said extensions and each opening both near the bottom and above the liquid level in the still local thereto, substantially as set forth.

5. In an apparatus for continuously distilling petroleum, the combination with a series of stills; of a series of short pipe connections which unite said stills, each to its nearest neighbor, in a continuous series, and, a series of long pipe connections structurally inde-

- pendent of each other and of said short pipe connections, arranged to unite non-adjacent stills and being disconnected from the intermediate stills, substantially as set forth.
5. 6. In an apparatus for continuously distilling petroleum, the combination with a series of stills; of pipe connections which unite said stills in a continuous series and determine the liquid levels in the respective stills and extending partly around the same; and, fire chambers located beneath said stills; the constructions and arrangement of said fire chambers and said pipe connections being such that the flames and products of combustion 15 are maintained out of contact with those portions of the walls of the stills which exist above their respective liquid levels, substantially as set forth.
7. In an apparatus for continuously distilling petroleum, the combination with a group of stills; of pipe connections respectively uniting said stills in pairs forming a continuous series; and means for regulating and controlling the flow of oil through the stills, 20 and maintaining the liquid levels at predetermined graduated heights in the individual stills of the series, substantially as set forth.
8. In an apparatus for continuously distilling petroleum, the combination with a group 25 of stills; of pipe connections respectively uniting said stills in pairs, forming a continuous series; and means connected to said pipe connections for regulating and controlling the flow of oil through the stills, and maintaining the liquid levels at predetermined graduated heights in the individual 30 stills of the series, substantially as set forth.
9. In an apparatus for continuously distilling petroleum, the combination with a group 35
- of structurally distinct and independent 40 stills; of pipes which respectively connect adjoining pairs of said stills to form a continuous series; a separate fire chamber beneath each still; and, flues, extending through one or more of the stills of the series below the 45 liquid level therein, and connecting the fire chambers of the stills in which they are located, with conveyers or stacks for the products of combustion, substantially as set forth.
10. In an apparatus for continuously distilling petroleum, the combination with a group of stills; of pipe connections by which adjoining individual stills are connected in pairs to form a continuous series; means for supplying oil to the first still of the series; a 50 heating coil located in the first still of the series; means for precisely controlling the heating effect of said coil; and, separate fire chambers respectively located beneath the remaining stills of the series, substantially as 55 set forth.
11. In an apparatus for continuously distilling petroleum, the combination with a group of stills; of pipe connections between the adjoining stills, each having an outlet 60 from one still and an inlet to another still; each of said outlets comprising a vertical pipe whose opposite ends open respectively near the bottom and above the liquid level in the still local thereto, substantially as set 65 forth.

In testimony that I claim the foregoing as my invention I have hereunto signed my name this 23d day of July, A. D. 1901.

MAX LIVINGSTON.
